THREAD TENSION ARRANGEMENT IN
TEXTILE MACHINES

Albert Brügger, Mergen, Switzerland

Application February 18, 1947, Serial No. 729,314
In Switzerland March 6, 1946

3 Claims. (Cl. 242—147)

1

The invention relates to improvements in roving and thread tension arrangements in spinning and twisting machines of the continuous type, comprising at least one thread-brake applying a braking action adjustable in accordance with a scale indicator.

A numerical setting of the thread tension or stretch in accordance with the character of the thread material and, if desired, with the use envisaged for the thread, thus is made possible.

One embodiment of the inventive tension arrangement, comprising two thread brakes, is shown in the accompanying drawing.

Fig. 1 shows an elevation of the arrangement, a scale equipped setting disc being illustrated for the one thread-brake only.

Fig. 2 is a partial view corresponding to Fig. 1, the setting disc, however, being shown in a different position.

Fig. 3 is a side elevation of Fig. 1, comprising in addition a setting disc provided for a thread brake.

Fig. 4 is a section on line IV—IV of Fig. 3 showing the setting disc in minimum tension position.

Fig. 5 is a similar section showing the setting disc in maximum tension position.

In Figs. 1 and 3, 1 denotes a frame standard provided on its upright leg 2 with a set of vertically stacked brake fingers 3. Brake fingers 4 are associated in vertical arrangement with the said fingers 3, staggered by half a finger-pitch relative thereto and secured to the web of a strap or stirrup 5 which is pivoted, by its two arms or flanges, on a pin 6 mounted in frame 1. Thus a finger brake of known type is formed, the running thread being threaded through the fingers thereof under a continuous change of direction or, respectively, in a circuitous path; strap 5 of the said thread brake being biased by a torsion spring 7 which tends to hold finger set 4 in the vertical plane of finger set 3. The upright leg 2 of frame standard 1, which latter is fixedly secured to the respective thread-handling machine, carries on a lower extension a lateral arm 8, on the free end of which a disc 10 is mounted by means of a cross-pin 9. The rim of disc 10 is spiral-shaped and provided with a scale, and disc 10 is adjustable in its angular position on pin 9 by means of a nut 11. Two friction discs 12, 13 are mounted loosely on lateral arm 8. Friction disc 12 laterally abuts against a collar 14 secured to arm 8, and friction disc 13 is pushed laterally against friction disc 12 by the action of a cone spring 15 mounted

2

on arm 8. Spring 15 at its other end abuts against a collar 16 which is axially displaceable on arm 8. Collar 16 by means of a projecting rim portion is biased by spring 15 into engagement with the rim of setting disc 10. Collar 16 representing, so to speak, a feeler ring, is provided with a mark (not visible in the drawing) in order to permit of accurately setting disc 10 with its scale relative thereto.

10 The textile thread, which is intended to be processed or threaded on the respective machine, passes, after leaving the thread brake described, between the two friction discs 12, 13. According to the angular position of setting disc 10 and the corresponding position of feeler ring 16 on arm 8, spring 15 is tensed more or less so that the thread is subjected in brake 12, 13 to a corresponding brake action. In Fig. 1, disc 10 is shown set for a maximum, and in Fig. 2 for a minimum brake action approximately, as may readily be seen.

In order to permit of numerically setting the tension of a running thread also within the range of the thread brake, a lower cantilever 17 is provided on frame 1 as shown in Fig. 3. Cantilever 17 having a boss 18 accommodates a pivot 19 on which the disc 20 is mounted. The latter is provided with a spiral-shaped rim carrying a scale, and is adjustable, with respect to its angle of rotation, on pivot 19 by means of a wing nut 21. A feeler pin 22 (Fig. 4) cooperates with the rim of setting disc 20, and is secured to swing strap 5 carrying brake fingers 4.

Feeler pin 22 is continuously pushed against the rim of setting disc 20 by the action of torsion spring 7 (Fig. 1), biasing strap 5 so that, in accordance with the position of rotation of disc 20, finger set 4 is moved more or less toward the vertical plane of stationary finger set 3 or, eventually, is swung into the said plane, as will be readily seen from Figs. 4 and 5. Disc 20 is set in Fig. 5 for maximum, and in Fig. 4 for minimum brake action approximately.

The tension arrangement obviously also may 45 comprise only one thread brake numerically adjustable according to the present invention, or eventually, however, also more than two such brakes.

The inventive tension arrangement also is 50 suited, aside from reducers, e. g., for winding frames, but also for other thread-processing or thread-treating textile machines.

What I claim and desire to secure by Letters
Patent is:

55 1. In a tension arrangement for running thread

in winding and other textile machines with at least one thread-brake, of the character described, a thread-tension adjusting means adapted to subject the thread to a numerically predetermined tension, comprising a spiral-shaped pivoted disc provided with a circumferential scale, clamping means for adjusting the rotary position of the said disc, a feeler collar mounted loose on the thread-brake pivot and provided with an index and adapted to engage the rim of the said disc, and a spring mounted between the thread-brake and the said collar for the purpose of pushing the latter into contact with the said disc and of subjecting the thread-brake to a braking action numerically corresponding to the setting of the disc relative to the said collar.

2. In a tension arrangement for running thread in winding and other textile machines with a thread-brake, of the character described, a thread-tension adjusting means adapted to subject the thread to a numerically predetermined tension, comprising a spiral-shaped pivoted disc provided with a circumferential scale, clamping means for adjusting the rotary position of the

5 said disc, and a feeler pin fixedly secured to the pivoted spring-loaded portion of the said thread-brake and abutting against the rim of the said disc, whereby the thread-brake, and thus the
10 5 thread passing there-through, is subjected to a braking action numerically corresponding to the setting of the disc relative to the said pin.

3. In a tension arrangement for running thread in winding and other textile machines with a
15 10 thread-brake and a thread-brake disposed independent of the latter, of the character described, an independent thread-tension adjusting means each for the said two brakes and adapted to subject the thread to a numerically predetermined tension, comprising each a spiral-shaped pivoted disc provided with a circumferential scale, clamping means for adjusting the rotary position of the said disc, and a spring-loaded feeler member abutting against the rim of said disc to bias the
20 15 adjustable brake portion into a position wherein the running thread is subjected to a tension numerically corresponding with the setting of the said disc.

ALBERT BRÜGGER.
